UNITED STATES PATENT OFFICE.

PERLEY R. GLASS, OF WAYLAND, MASSACHUSETTS, ASSIGNOR TO UNITED SHOE MACHINERY CORPORATION, OF PATERSON, NEW JERSEY, A CORPORATION OF NEW JERSEY.

FASTENER-INSERTING MACHINE.

Application filed February 2, 1923. Serial No. 616,601.

This invention relates to fastener-inserting machines and more particularly to the type comprising mechanism for inserting the fasteners in thin sheet material and a raceway for supplying the fasteners to said mechanism. The accompanying drawings illustrate the invention in connection with a machine for setting lacing-hooks in shoe uppers, a machine of this same general organization being more fully shown and described in United States Letters Patent No. 1,512,922, granted October 28, 1924, on my application.

One object of this invention is to provide improved means for separating the leading hook in the raceway from the succeeding hooks and for advancing the leading hook into the path of a transferring member while arresting the succeeding hooks. Accordingly a feature of the invention consists in improved automatic means comprising a member formed and arranged to enter between the first and second hooks in the raceway and to feed the first hook positively, though preferably by means of a yielding connection, into register with a transferring member. The qualification "positively" is not here used in the sense that implies rigidity but in the sense that implies a definite action in contra-distinction to the more common type of hook separator that is more strictly an escapement and merely releases the leading hook which then depends upon the force of gravity to advance it from the point of separation to its objective position in the path of a transferring member.

Another object of the invention is to provide improved means for maintaining the work against accidental displacement during its periods of rest by which the feeding steps are separated. The illustrated machine, like most hook-setting machines, comprises a hook-carrier for inserting the hooks into the work, said carrier having a plate portion adapted to occupy the throat of the hook between the head and the barrel portion. This hook-carrier, after inserting a hook, is shifted laterally to clear the throat of the hook before it is retracted from the work, and slides with more or less pressure on the hook or on the work or on both incidentally to executing its throat-clearing movement. The frictional drag of the hook-carrier on the work, as it moves laterally to

clear the throat of the set hook has a tendency to displace the work, and although former practice has provided a presser-foot at the receiving side of the setting locality, I have found that the work may be held more securely by supplementing such presser-foot with one arranged to clamp the work at the delivery side of the setting locality.

A feature of the present invention therefore consists in a combination comprising work-supporting means and two cooperative devices arranged to coact with said means to clamp the work at opposite sides of the setting locality.

Still another feature of the invention consists in providing a presserfoot on the carrier of one of the hook-setting tools in such relation that the presser-foot is moved to and from operative position by said carrier. This feature utilizes the motion of one of the hook-setting tools to operate a presserfoot and avoids encumbering the organization with additional mechanism for the purpose. As shown, the presserfoot so operated is carried to and from the work by the carrier of one of the hook-setting tools, but it would be within the scope of the invention to use the said carrier to move the presserfoot to and from the work even if the presserfoot were mounted otherwise than on said carrier.

Referring to the accompanying drawings, which illustrate the various features of the present invention embodied in a preferred form and according to a preferred organization—

Figure 1 is a front elevation partly in section of a fragment of a hook-setting machine, the several parts occupying their initial positions;

Fig. 2 is a view similar to Fig. 1 showing the hook-engaging members as having completed the clenching of a lacing-hook but being still in engagement with the clenched hook;

Fig. 3 is a perspective view of the auxiliary presser-foot;

Fig. 4 is a top plan view partly in section of the delivery end of the hook raceway and the devices for separating the hooks and transferring them to the hook-carrier;

Fig. 5 is a view similar to Fig 4 showing the parts in different positions;

Fig. 6 is a perspective view including the hook-carrier, the member for transferring the hooks thereto, and the hook-separator and feeder; and .

5 Fig. 7 is a perspective view of the hook-separator and feeder.

To facilitate reference to my said Letters Patent I have used herein the same reference numerals that are used therein to designate corresponding elements, and it is to be understood that the construction, general organization and operation of the machine are the same as in the patented construction excepting that the latter does not include 10 the hook-separator and feeder or the auxiliary presser-foot hereinafter described and claimed.

The lacing-hooks gravitate on a raceway strip 61 from a supply hopper to a point 20 nearly in register with the reciprocatory transferring member 69, the strip 61 being formed to occupy the throats of the hooks. A guard strip 66 is arranged to engage the barrel portions of the hooks to keep the 25 hooks on the strip 61. The delivery end of the raceway is above the work and the hooks are therefore inserted right side up. Consequently, as the hooks reach the delivery end of the raceway their heads lie on 30 the upper surface of the strip 61 and their barrel portions are suspended under said strip.

The transferring member 69 transfers the hooks one by one to a hook-carrier 46 which 35 is movable horizontally as may be seen by reference to Figs. 4 and 5, and which is also movable vertically as may be seen by reference to Figs. 1 and 2. The hook-carrier is arranged to slide horizontally in guides 40 at the lower end of a plunger 48 and is provided with a stem 47 (Fig. 6) which extends through the plunger and has tongue-and-groove connection with a horizontally movable plunger 78. The tongues of this connection are provided by a plate portion 80 fastened to the stem 47 while the grooves are formed in a head at the forward end of the plunger 78. This construction is such that the hook-carrier 46 partakes of horizontal reciprocation of the plunger 78 while the tongue-and-groove connection permits it also to partake of vertical reciprocation of the plunger 48 and to remain positively under control of both plungers at all times.

55 The raceway is so constructed, near its delivery end, as to impart an angle to the path of travel of the hooks. Consequently, since the hooks advance sidewise in approaching this angle it becomes possible for 60 them to advance beak foremost from the angle to the hook-carrier 46. Furthermore, the abrupt change of direction afforded by the angle permits the transferring member 69 to move in the same direction as the hook 65 on which it acts, so that the impelling action

of the transferring member may be a direct thrust in the direction of transfer. This angle in the raceway is shown in Fig. 4 and is formed by the upper edge and right hand edge of the strip 61 and by the complementary member 70 that defines one side of the delivery portion of the raceway.

A lacing-hook, having reached the aforesaid angle where it is indicated at 68 in Fig. 4, is supported in part by the end of the raceway strip 61 and in part by a displaceable supporting member 71. The latter is arranged to oscillate on a pivot member 72 and is normally maintained by a light spring 73 in the position shown by Fig. 4, in which position it forms, in effect, a short continuation of the raceway strip 61. When the parts are in the position shown by Fig. 4 the plate portion of the hook-carrier 46 is at the same level as the delivery end of the raceway but the hook-carrier is separated horizontally from the raceway in consequence of having been moved laterally to clear the throat of the preceding clenched hook. The horizontally movable plunger 78 and the hook-transferring member 69 are interconnected to move in unison, but the connection is such that when one is moved to the rear the other moves to the front and vice versa. Consequently, when the transferring member 69 moves toward the hook-carrier 46 the latter moves toward the raceway and reaches the position shown by Fig. 5 in time to receive the hook before the latter has lost the support of the raceway.

The plunger 48 now descends to insert the hook, the front vertical edge 77 of the plunger 69 having a depth sufficient to maintain contact with the neck of the hook until the latter is clenched as shown by Fig. 2. This figure shows an article of work 10 such as a shoe upper comprising two layers of material. The work lies on the work-support 11 and is under continuous pressure by a presser-foot 12. The barrel portion of the hook, while passing through the work 10, surrounds the pilot portion 21 of the clenching tool 14, the latter having previously been raised to cause the pilot portion 21 to punch a hole in the work. The barrel portion of the hook therefore encounters the clenching tool 14 and is clenched, as shown by Fig. 2, by the downward movement of the plunger 48 while the clenching tool remains stationary. The plunger 48 remains at its lowest position while the hook-carrier 46 is moved horizontally to clear the throat of the clenched hook, but before the hook-carrier starts to execute this lateral movement the clenching tool 14 is lowered sufficiently to relieve the clenching pressure. Notwithstanding such relief of pressure it frequently happens that the hook-carrier 125 has a small component of pressure on the

work and sometimes on the upper end of the barrel portion of the hook during that period when the carrier is moving laterally to clear the throat of the hook, and although the 5 presser-foot 12 tends to maintain the work against lateral displacement it is effective only at one side of the setting locality. Accordingly one of the novel features of the present invention consists in an auxiliary 10 presser-foot 125 arranged to clamp the work at the opposite side of the setting locality with reference to the main presser-foot 12.

The presser-foot 125 is formed with a stem 126 and is arranged to slide in a boss 15 127. To provide for removing the member 125 periodically from the path of feeding movement of the clenched hook and at the same time to avoid complicating the machine with special mechanism for this purpose I prefer to attach the auxiliary presser-foot to the plunger 48. Accordingly the boss 127 is formed on the plunger 48. A compression spring 129 exerts downward pressure on the shoulder 130 of the stem 126 to furnish 20 the pressure by which the work is clamped against the work-support 11. The upper end of the stem 126 projects above the boss 127 and is threaded to take binding nuts 131, the latter being adjustable to regulate 25 the initial position of the member 125 relatively to the hook-carrier. In practice the member 125 will be so adjusted that it will engage the work before the barrel portion of the hook has passed through the latter. 30 Consequently the member 125 will remain stationary during the latter stages of downward movement of the plunger 48 and the compression of the spring 129 will be increased. The work will therefore be securely clamped at opposite sides of the 35 clenching locality as shown by Fig. 2 during the inserting and clenching of the hook and also while the hook-carrier is moving laterally to clear the throat of the clenched hook. 40 Also, during the first stages of upward movement of the plunger 48 the member 125 will maintain its clamping action on the work, the extent of lost motion between the nuts 131 and the boss 127 determining the 45 point in the upward movement of the plunger 48 at which the member 125 releases the work. The upward travel of the plunger 48 is sufficient to raise the member 125 well above the level of the head of the clenched 50 hook, and since the machine is organized to cause the punching element 21 to feed the work periodically from right to left the hook may pass under the member 125 without interference. 55 Instead of relying upon the force of gravity to advance the leading hook in the race-way to the position indicated at 68 in Fig. 4, I have provided an improved hook-separator and feeder 117 which advances the leading hook one step and temporarily restrains the 60 remaining hooks by engagement with the barrel portion of the second hook. The member 117, as shown is in the form of a plate and has a wedge-shaped extremity adapted to enter between the barrel portions 70 of the first and second hooks. The edge 118 is parallel to the lines of movement of the device and is therefore adapted to obstruct the path of the remaining hooks without forcing them back or otherwise disturbing 75 their positions in the raceways. To provide for the necessary movement of the member 117 without complicating the machine by the addition of special mechanism for that purpose I prefer to attach said member to the 80 grooved head at the forward end of the horizontally movable plunger 78 from which the hook-carrier 46 receives its horizontal motions. The member 117 is therefore provided with a tubular body portion 119 85 through which an attaching screw 120 extends, the forward end of said screw being screwed into a hole tapped in the rear side of the head of the plunger 78 as shown by Fig. 4. A compression spring 121 is seated 90 against the head of the screw 120 and exerts its pressure against the member 117 to maintain the latter normally against the rear face of the plunger head, the spring constituting a yielding connection adapted to afford lost 95 motion so that the member 117 may be arrested without causing breakage or bending of the parts while the plunger 78 continues to move forward. For example, when the hook-carrier 46 is moved laterally to clear 100 the throat of the clenched hook the pointed end of the member 117 passes under the race-way strip 61 and enters between the barrel portions of the first and second hooks. At this time the first hook is against the transferring member 69 as shown by Fig. 5, and cannot move to the right. The first hook therefore arrests the member 117, but such arresting is only temporary because while the plunger 78 is moving forward the transferring member 69 moves backward and releases the first hook. When such release occurs the spring 121 reacts and imparts further advance movement to the member 117, 105 thereby causing the latter, by its wedging 110 action on the barrel portion of the first hook, to shift the latter into the angle of the race-way where it lies in the path of the member 69. The separated hook is thus moved to the position indicated at 68 in Fig. 4 at 115 which position it is arrested by a stationary member 70. The capacity of the member 117 to yield also guards against bending or breakage of the parts in case an imperfect hook or an improperly positioned hook resists the forward movement of said member 120 in some abnormal fashion. 125

The clenching tool 14 is carried by a vertically movable plunger 15 and stands initially below the level of the work-support 11 130

and in register with a punch-block 22. To place an article of work in position to receive lacing-hooks the operator first raises the plunger 23 manually. This plunger carries the punch-block 22 and the presser-foot 12. Having placed the work in the desired position he releases the plunger 23 which is automatically lowered and maintained rigidly in the position shown by Figs. 1 and 2, the punch-block being then slightly above the work and occupying a recess formed in the presser-foot 12. A spring-stressed device maintains the pressure of the presser-foot 12 on the work continuously so long as the plunger 23 is in its lowest position. On starting the machine the plunger 15 rises to project the punching element 21 through a slot 13 in the work-support and through the aforesaid notch or cavity in the presser-foot 12, said punching element rising until it has passed through the work and is engaged by the punch-block. The mechanism for operating the plunger 15 then relieves the pressure against the punch block and maintains the punch 21 in the work while automatic work-feeding mechanism causes the plunger 15 to move from right to left. The feeding movement ends when the clenching tool is in vertical register with the hook supported by the hook-carrier 46, and the tool then has a period of rest during which the hook is inserted and clenched as hereinbefore explained.

Having thus described the invention, what I claim as new and desire to secure by Letters Patent of the United States is:—

1. In a machine for setting lacing hooks, a hook-sustaining member adapted to occupy the throat of a hook during the setting operation, a raceway arranged to supply hooks to said member, a reciprocatory operating member engaging said hook-sustaining member to move the latter out of the throat of the set hook, and a hook-separator carried by said operating member to separate a hook in the raceway from those behind it.

2. In a machine for setting lacing hooks, a hook-sustaining member adapted to occupy the throat of a hook during the setting operation, a raceway arranged to supply hooks to said member, a reciprocatory operating member engaging said hook-sustaining member to move the latter out of the throat of the set hook, and yielding means carried by said operating member to separate a hook in the raceway from those behind it.

3. In a machine for setting lacing hooks, a raceway for supplying lacing hooks, a hook-sustaining member adapted to occupy the throat of a hook during the setting operation, said member being movable to transfer the hook from the raceway to the work and being movable laterally to clear the throat of the set hook, a reciprocating operating member engaging said hook-sustaining mem-

ber to move it laterally, and means carried by said operating member to separate a hook in the raceway from those behind it.

4. A machine for setting lacing hooks comprising a hook-setting member adapted to occupy the throat of a lacing hook, a raceway arranged to supply hooks to said member, means arranged to transfer a hook from the raceway to said member, an operating member engaging said setting member to move it laterally out of the throat of the set hook, and means carried by said operating member to separate a hook in the raceway from those behind it and to move said hook into register with said transferring means. 80

5. A machine for setting lacing hooks comprising a hook-setting member adapted to occupy the throat of a lacing hook, a raceway arranged to supply hooks to said member, means arranged to transfer a hook from the raceway to said member, an operating member engaging said setting member to move it laterally out of the throat of the set hook, and yielding means carried by said operating member to arrest all the hooks in the raceway excepting the leading hook and to move the latter into register with said transferring means. 90

6. A machine for setting lacing hooks comprising a hook-setting member adapted to occupy the throat of a lacing hook, a raceway arranged to supply hooks to said member, means arranged to transfer a hook from the raceway to said member, an operating member engaging said setting member to move it laterally out of the throat of the set hook, and a wedge member carried by said operating member to move the leading hook in the raceway into register with said transferring member. 100

7. A machine for setting lacing hooks comprising a hook-inserting member, a raceway arranged to supply lacing hooks thereto, the delivery end of said raceway being stationary and having an angle to change the direction of travel of the hooks, means arranged to arrest the second hook at the supply side of said angle and move the first hook into the angle, and means arranged to transfer the latter said hook from said angle to said hook-inserting member. 110

8. A machine for setting lacing hooks comprising a work-support, a hook-setting member, a carrier by which said member is carried toward and from the work, and a presserfoot arranged to be operated by said carrier to clamp the work against said work-support. 120

9. A machine for setting lacing hooks comprising a work-support, a hook-setting member, a carrier by which said member is carried toward and from the work, and a presserfoot carried by said carrier to clamp the work against said work-support. 125

10. A machine for setting lacing hooks 130

comprising a carrier movable toward and from the work, and a hook-setting member and a presserfoot both carried by said carrier, said hook-setting member being adapted to occupy the throat of the hook and being laterally movable to clear the throat of the set hook while said presserfoot is holding the work.

11. A hook-setting machine comprising work-supporting means, two separate presserfeet arranged to cooperate therewith to clamp the work, and mechanism arranged to set a hook between said presserfeet, said mechanism including a member movable toward and from the work, and one of said presserfeet being operated by said member.

12. A machine for setting lacing hooks comprising work-supporting means, means for feeding the work, a presserfoot arranged and operated to engage the work intermittently, a presserfoot arranged to engage the work continuously, and a hook-setting member adapted to occupy the throat of the hook and movable laterally to clear the throat of the set hook while the work is held by both of said presserfeet.

13. A machine for setting lacing hooks comprising work-supporting means, two relatively movable presserfeet spaced apart from each other and arranged to coact with said means to clamp the work, and mechanism arranged to set a hook between said presserfeet.

14. A machine for setting lacing hooks comprising work-supporting means, two relatively movable presserfeet spaced apart from each other, mechanism arranged to set a hook between said presserfeet, said mechanism including a hook-carrier adapted to occupy the throat of the hook and movable laterally to clear the throat while the work is held by both of said presserfeet.

15. A machine for setting lacing hooks comprising work-supporting means, two relatively movable presserfeet spaced apart

from each other and arranged to coact with said means to clamp the work, and mechanism arranged to set a hook between said presserfeet, said mechanism including a member movable toward and from the work, one of said presserfeet being arranged to be operated by said member.

16. A hook-setting machine comprising mechanism for setting lacing hooks, means for feeding the work, and a presserfoot, said setting mechanism including a hook-engaging tool and a carrier for moving it toward and from the work, and said presserfoot being carried by said carrier and arranged to engage the work in the feed-path of the set hook.

17. A hook-setting machine comprising mechanism for setting lacing hooks head up, means for feeding the work, and a presserfoot, said setting mechanism including a setting tool adapted to occupy the throat of the hook and a carrier for moving said tool toward and from the work, and said presserfoot being carried by said carrier and arranged to engage the work in the feed-path of the head of the set hook.

18. A machine for setting lacing hooks comprising a work-support, means for feeding the work to space the hooks, a hook-inserting member, a reciprocatory carrier for the latter, and a presserfoot arranged to cooperate with said work-support and to be operated by said carrier to clamp the work between feeding steps.

19. A machine for setting lacing hooks comprising a work-support, means for feeding the work to space the hooks, a hook-inserting member, a reciprocatory carrier for the latter, and a presserfoot carried by said carrier and arranged to cooperate with said work-support to clamp the work between feeding steps.

In testimony whereof I have signed my name to this specification.

PERLEY R. GLASS.
